Attorney

UNITED STATES PATENT OFFICE.

FRITZ E. YORK, OF EARLVILLE, NEW YORK.

ROAD-SCRAPER AND STONE-REMOVER.

1,233,008.

Specification of Letters Patent. Patented July 10, 1917.

Application filed October 11, 1916. Serial No. 125,061.

To all whom it may concern:

Be it known that I, FRITZ E. YORK, a citizen of the United States, residing at Earlville, in the county of Madison and State of New York, have invented certain new and useful Improvements in Road-Scrapers and Stone-Removers, of which the following is a specification, reference being had to the accompanying drawings.

10 This invention relates to an improved road scraper and has for its primary object to provide a very simple and efficient device for scraping the road surface and eliminating irregularities therein and also collecting or gathering loose stone, the device being so constructed as to direct the earth to one side of the road while the stones are directed toward the opposite side thereof.

15 It is a more particular object of the invention to provide a device for the above purpose including a plurality of sectional scrapers hingedly connected for relative vertical movement, said scrapers being obliquely disposed across the road surface, and 20 a plurality of toothed stone gathering rakes or combs flexibly connected to the sectional scraper and disposed obliquely across the road surface in a relatively opposite direction with respect to the scraper.

25 It is a further object of the invention to provide a road scraper which consists of relatively few parts of very simple construction so that the device is not liable to get out of order, and may be manufactured at relatively small cost.

30 With the above and other objects in view, my invention consists in the novel features of construction, combination and arrangement of parts to be hereinafter more fully 35 described, claimed and illustrated in the accompanying drawing, in which,

35 Figure 1 is a top plan view of a road scraper constructed in accordance with the preferred embodiment of the invention; and 40 Fig. 2 is a longitudinal section thereof.

45 Referring in detail to the drawing, 5 designates a series of platform sections. These sections are arranged in pairs disposed in the same plane, the sections in each pair 50 overlapping upon the longitudinal edges of the next adjacent platform sections. The sections in the front and rear pairs are hingedly connected to each other, as at 6, and the overlapping edges of said platform 55 sections are securely fixed to each other. The central pair of sections 5 are not hing-

edly connected but their inner opposed ends may move freely with respect to each other in the relative vertical movement of the hingedly connected sections of the platform. 60 To the forward longitudinal edge of each of the platform sections 5, a steel scraping strip 7 is secured.

To the ends of the rear scraper sections 5, the rearwardly extending bars 8 and 9 of 65 relatively different lengths, are fixed. These bars, at their rear ends, are connected to each other by means of a series of slats 10, said slats being connected by hinges 11. By the provision of the bars 8 and 9 of different 70 lengths, the series of slats 10 are positioned obliquely with respect to the platform sections. The ends of a pair of chains 12 are loosely attached to the rear platform sections 5 and to the bar 9. These chains drag 75 upon the road surface in the travel of the machine and collect the larger loose stones lying upon the road surface.

Rearwardly of the series of hingedly connected slats 10 and in parallel relation thereto, a series of rakes 13 are arranged, said rakes being disposed in overlapping relation and spaced from each other longitudinally of the machine, the left hand end of the rear rakes each being loosely connected by bolts 80 14 to the adjacent rake at the approximate center of the latter. The right hand ends of the forward rakes are connected by short lengths of chains 15 to the next rake in the rear. In this manner, the several rakes are 85 flexibly connected. A relatively large rake 17 is disposed rearwardly of the series of short rakes 13 in spaced relation thereto and is connected by means of the bars 18 to the two rear rakes 13. The ends of the bars 18 extend beneath the respective rake bars 13 and 17. Obliquely disposed brace rods 16 connect the rear ends of the bars 18 to certain of the rakes 13. The bars 18 have scraping engagement with the ground surface and direct the stones which escape the 90 rake 13 toward the center of the road. The teeth of the rakes 13 are vertically disposed, while the rake 17 preferably has its teeth 95 rearwardly curved, as shown. Chains or cables 19 are connected to the rakes 13 and to the rear edge of the scraper platform. It 100 will be understood that any suitable draft attachments may be provided on the forward edge of the scraper platform for connecting the draft animals thereto.

105 In the operation of the machine, as the

same is drawn over the road, indicated in dotted lines in Fig. 1, the blades or strips 7 attached to the forward edges of the platform sections 5, scrape the loose dirt from the road surface and direct the same toward the left hand side of the road, the platform extending obliquely across the roadway. As the platform sections are flexibly connected, they may move relative to each other and thus enter ruts or depressions in the road surface. The loose chains 12 direct the large rocks or stones toward the right hand side of the road. The smaller stones are collected by the several rakes 13, and such stones as may pass over these rakes or escape the same will be gathered by the rake 17. The rakes 13 and 17 also discharge the larger stones collected thereby toward the right hand side of the road. The very small stones and the remaining loose earth being directed by the bars 18 toward the center of the road, is separately gathered or collected, as it may be desired to use the finer material for use in making repairs or other purposes. Thus, it will be seen that the loose dirt or earth scraped from the road surface is discharged in one direction while the stones are discharged in an opposite direction so that the latter may be readily gathered. It will, therefore, be apparent that my improved road scraper is very serviceable and convenient in practical use and provides means for quickly and smoothly leveling the road surface.

35 From the foregoing description, taken in connection with the accompanying drawing, the construction, manner of operation and several advantages of the device will be fully understood. The several parts of the machine are exceedingly simple and durable in construction and highly efficient and reliable in operation. The machine may, of course, be manufactured in various sizes and at relatively small cost.

40 While I have shown and described the preferred construction and arrangement of the several parts, it is to be understood that the device is susceptible of considerable modification therein and I, therefore, reserve the privilege of adopting all such legitimate changes as may be fairly embodied within the spirit and scope of the invention as claimed.

Having thus fully described my invention, 55 what I desire to claim and secure by Letters Patent is:—

1. In a road scraper, a plurality of spaced, parallel, scraping members adapted to extend obliquely across the road surface to scrape the top soil therefrom and direct the

same toward one side of the road, and a stone gathering rake flexibly connected to the series of scrapers and disposed in spaced relation to the same rearwardly thereof and at an oblique angle in an opposite direction 65 to the scrapers across the road surface to direct the stones toward the opposite side of the road.

2. In a road scraper, a plurality of spaced, parallel, scraping members adapted to extend obliquely across the road surface to scrape the top soil therefrom and direct the same toward one side of the road, a series of spaced, parallel, stone rakes arranged rearwardly of the scrapers to extend obliquely across the road surface in an opposite direction to the scrapers and direct the stones toward the opposite side of the road, and means flexibly connecting the rakes to each other and to the scrapers. 80

3. In a road scraper, a plurality of spaced parallel scraping members adapted to extend obliquely across the road surface to scrape the top soil therefrom and direct the same toward one side of the road, a series 85 of spaced, parallel, stone rakes arranged rearwardly of the scrapers to extend obliquely across the road surface in an opposite direction to the scrapers and direct the stones toward the opposite side of the road, 90 an additional rake disposed rearwardly of said series of rakes and in parallel relation thereto, and means flexibly connecting the stone rakes to the scrapers.

4. In a road scraper, a series of platform 95 sections flexibly connected for relative vertical movement, a metal scraping bar fixed to the forward edge of each of the platform sections, rearwardly extending bars of relatively different lengths fixed to the rear sections of the platform, a series of hingedly connected slats connecting said bars, said platform sections being obliquely disposed to the line of travel whereby the soil is directed by the scraper bars toward one side 100 of the road, a series of flexibly connected rakes disposed rearwardly of said hingedly connected slats and obliquely across the road surface in an opposite direction to the platform sections to direct stones toward the 110 opposite side of the road, and flexible means connecting said rakes to the sectional platform.

In testimony whereof I hereunto affix my signature in the presence of two witnesses. 115
